UNITED STATES PATENT OFFICE.

BENJAMIN OGUSH, OF NEW YORK, N. Y., ASSIGNOR TO KATZ & OGUSH, INC., OF NEW YORK, N. Y., A CORPORATION OF NEW YORK.

FASTENING DEVICE FOR WRIST WATCHES.

Application filed April 27, 1928. Serial No. 273,224

This invention relates to an improvement in a fastening device for holding the wrist surrounding member of a wrist watch in position. It has for its object to provide a form of clasp which will be particularly applicable for use upon a cord-type of wrist band.

The structure produced according to my invention is one of simple construction and few parts thus being extremely unlikely to get out of order, at the same time affording a very firm and secure connection.

A further object of the invention is to provide a form of clasp for use upon a wrist cord, which clasp shall be so arranged that whether the same is open or shut, the wrist cord will remain in complete loop-like formation so that the possibility of the watch being lost from the wrist will be wholly avoided.

A still further object of the invention is to provide a form of clasp which will permit a spreading or expansion of the wrist loop to permit the same being readily expanded so that the watch may be placed on or removed from the wearer's wrist.

With these objects, and such other objects as may hereinafter appear in view, I have devised the particular arrangement of parts hereinafter set forth and more particularly pointed out in the claims appended hereto.

Reference is to be had to the accompanying drawing, forming a part hereof in which

Figure 1 is a front elevation of a watch provided with a wrist encircling cord and showing my improved clasp in position thereon;

Figure 2 is a view of the rear face of one of the clasp members;

Figure 3 is a view of the rear face of the male member of the clasp;

Figure 4 is a sectional view on the line 4—4 of Figure 2, looking in the direction of the arrows;

Figure 5 is a sectional view on the line 5—5 of Figure 3 looking in the direction of the arrows;

Figure 6 is a sectional view on the line 6—6 of Figure 1 looking in the direction of the arrows; and

Figure 7 is a front view of the clasp.

Throughout the various views of the drawings, similar reference characters designate similar parts.

In the embodiment of my invention disclosed in the accompanying drawing, 1 indi-

cates a form of wrist watch. The watch herein shown is provided at its opposite ends with a pair of openings 3 and 4 through which a single continuous cord 5 is looped as is shown in Figure 1. This cord may be of silk or some other like material or it may be of metal. The two ends of the cord are shown at 6 and 7 and these ends are secured to a pair of fastener members now to be described. One of these fastener members is shown at 8 and the same is the female member. This fastener member 8 is provided with a continuous tubular guide 9 through which the cord 5 freely passes so that the member 8 is movable on that portion of the cord which passes through the guide 9.

The end 6 of the cord is secured in a short tubular socket member 10 which is located adjacent to the edge of the member 8 opposite to that at which the tubular guide 9 is located. In order to firmly secure the end 6 of the cord in place in the socket 10, I provide said socket with holes 11, through which securing stitches 12 may pass.

It will be seen that there is an intervening space located between the members 9 and 10 and in this space is located an elongated aperture or slot 13. This slot 13 is adapted to receive an elongated stud 14 extending from the inner face of a male fastener member 15. The male fastener member 15, shown in detail in Figures 3 and 5 is in the nature of a flat plate with curved ends 16 and 17.

Extending outwardly from the inner face of the plate 15 is a short socket member 18 in which is securely fitted the end 7 of the cord 5. This end 7 of the cord is secured within the socket 18 in a manner similar to that by which the opposite end 6 on the cord is secured within the socket 10. That is, fastening stitches 19 are utilized, these stitches passing through holes 20 provided in the socket 18 for their reception.

It will thus be seen from the foregoing that the fastening device consists of a pair of substantially flat or plate-like members adapted to interlock. Such interlocking is caused by an inter-engagement of a U-shaped spring 21 which is provided on the inner face of the fastener member 8 with the sides of the stud 14. This spring has a pair of arms 22 and 23, which lie co-extensive with the longitudinal edges of the aperture 13 and protrude a slight distance in from said edges. Thus, when the plates 8 and 15 are placed in over-

lapped relationship as is closed clearly in Figure 6, the stud member 14 is projected through the aperture 13 and the spring arms 22 and 23 snap into frictional engagement with longitudinal grooves 24 provided in the sides of the stud member 14.

Through the arrangement just described, the two fastener members 8 and 15 are securely attached together although the same are readily detachable from one another. To facilitate a detachment of one of the parts from the other, the plate 15 is provided with a projecting finger piece 25 on one of its edges which can be readily engaged by the finger nail and lifted to cause the stud 24 to be drawn out of engagement with the spring arms 22 and 23 and to consequently separate the two members. The spring 21 is preferably made of a section of bent resilient wire and it has its closed or looped end firmly secured to a downwardly bent flange 26 provided on the inner face of the member 8.

The outer ends of the spring arms 22 and 23, shown at 27, are preferably anchored in one of the ends of the plate. It will be noted in Figure 2 that a portion of the member 8 is cut away as at 28 so that the laterally projecting socket member 18 on the plate 15 can fit into such cut-out portion and align itself with the member 10. This arrangement materially decreases the thickness of the device and produces a uniform appearance on the inner face of the clasp.

It will be seen in Figure 7 that the outer face of the plate member 15 is extremely smooth and free from projecting edges or parts. This smooth outer surface may be set with precious stones or engraved or ornamented in any other way.

The curved edges 16 and 17 permit the plate 15 to conform smoothly to the rounded members 9, 10 and 18 so that the entire device presents a very pleasing appearance.

From the foregoing, the manner in which the device is used will be readily understood. In Figure 1, a watch and an attached wrist cord is shown. Here the clasp is in its closed position with the plates overlapped and interengaged as was previously described. When in this position, the wrist cord forms a continuous uniformly looped member, which holds the wrist watch snugly on the wrist. To remove the watch, the fastener members 8 and 15 are separated by raising the plate 15 by lifting the thumb piece 25. Thereupon, the two ends 6 and 7 of the cord are separated and the loop can be enlarged to a great extent to permit the watch to be readily slipped off the wrist. This is facilitated by the fact that the member 8 may be freely slid on the cord since a portion of the cord is slidable through the guide 9.

Having described one embodiment of my invention, it is obvious that the same is not to be restricted thereto, but is broad enough to

cover all structures coming within the scope of the annexed claims.

What I claim is:—

1. A clasp of the class described comprising a pair of fastener members, one of said members having an opening, the other member having a stud adapted to fit therein and detachably unite the members, an attaching cord, means on each of the fastener members for receiving and holding one end of said cord, and a guide member on one of the fastener members through which said cord may freely slide.

2. A clasp composed of a pair of plate-like fastener members, each of said members having a socket member at its rear adapted to receive one end of a wrist-embracing cord, a snap connection between both fastener members for holding the same detachably united, and a guide at the rear of one of the members through which the wrist-embracing cord may freely slide.

3. A clasp composed of a pair of plate-like fastener members, one of said members having a pair of spaced tubular parts on its rear face, one of said tubular parts being adapted to fixedly receive an end of a wrist-embracing cord, the other tubular part being adapted to form a guide through which a part of said cord may slide, means on the other member adapted to fixedly receive the other end of said cord, and means for providing a snap engagement between the two fastener members.

4. A clasp of the character described comprising a pair of flat plate-like members, one of said members having a pair of spaced tubular parts on one of its faces, one of said tubular parts forming a socket for the reception of one end of a wrist-embracing member, the other tubular part forming a guide through which said wrist-embracing member may move, means located between the tubular parts for affording a snap connection with the other fastener member and a tubular socket on the last-mentioned fastener member for receiving the opposite end of the wrist-embracing member.

5. A clasp for uniting the opposite ends of a continuous, looped wrist-embracing cord, said clasp being composed of a pair of overlying clasp members, one of said members having an opening, the other member having a stud adapted to fit in said opening, means on the perforated member for resiliently engaging the stud on the other member, a securing socket on the rear face of each of the clasp members for attaching to the opposite ends of the wrist-embracing cord, said socket adapted to lie in alignment when the two clasp members are engaged, and a guide on the perforated member through which a part of the cord may slide.

Signed at the city, county and State of New York, this 26th day of April, 1928.

BENJAMIN OGUSH.
